COIN OPERATED RELEASE MECHANISM AND CHANGE-MAKER FOR FREEING A SELEC- TIVE DISPENSING DEVICE FOR OPERATION

Louis Steiner, Belle Harbor, N. Y., assignor to Mills
Industries, Incorporated, a corporation of Illinois

Application April 1, 1948, Serial No. 18,444

3 Claims. (Cl. 194—2)

This invention relates to coin operated vending machines and more particularly to a coin operated release mechanism and change-maker adapted for use in conjunction with vending machines from which articles of merchandise may be selectively vended from a plurality of chutes or columns.

An important object of the invention is to provide a coin controlled release mechanism which will operate to free a vending device for a single vending movement when a predetermined number of coins have been received by said release mechanism.

Another object of the invention is to provide a release mechanism of the character described which may be selectively adjusted to free said vending device for operation to vend a twenty-five cent article of merchandise, for example, when a U. S. quarter or any combination of nickels and dimes equal to twenty-five cents has been received by said mechanism.

A further object of the invention is to provide a release mechanism of the above character which may be selectively adjusted to release a vending device for a single vending movement to discharge a ten-cent, fifteen-cent or a twenty-cent article of merchandise when any combination of nickels or dimes equal to the value selected have been received by the release mechanism.

Still another object of the invention is to provide in combination with a vending device embodying means for selectively vending articles from a plurality of chutes or the like, a release mechanism of the character described which may be selectively adjusted to free said device to vend articles of one price from a majority of said chutes when a combination of coins equal to said price have been received by the mechanism and to likewise free said device to vend articles of a lesser price from the remainder of said chutes when a combination of coins equal to said lesser price have been received.

A further object of the invention is to provide in combination with a selectively adjustable release mechanism, of the character stated, for freeing a dispensing device for dispensing operation, a coin dispensing means activated by said release mechanism to dispense a nickel or a dime as change when a coin or coins received by the latter are of a value five or ten cents in excess of the value at which said mechanism is adjusted to free said dispensing device.

Yet another object of the invention is to provide in a release mechanism of the character described, an improved manually operated means for releasing coins therefrom prior to operation of the dispensing device.

A further object of the invention is to provide in a vending machine having a plurality of separate groups of columns from which merchandise may be selectively vended, a release mechanism of the character stated conveniently disposed in a space between adjacent groups of said columns.

Other objects and advantages of the invention will be apparent from the following description of a preferred

2

embodiment thereof, taken in connection with the accompanying drawings, in which:

Fig. 1 is an elevational view of a dispensing machine of a type within which the invention may be embodied, of a portion of a front panel as well as other parts of the machine being cut away;

Fig. 2 is a plan sectional view of the machine shown in Fig. 1 illustrating the general disposition of main chutes for articles to be dispensed, auxiliary chutes therefor, and 10 penny change tubes;

Fig. 3 is a plan sectional view of the machine within which the invention may be embodied, showing one of a plurality of reciprocating dispensing bars in its normal position;

Fig. 4 is an enlarged fragmentary sectional view, similar to that shown in Fig. 3, showing one of the reciprocating dispensing bars in its extended position and showing mechanism for preventing movement of more than one bar at a time;

Fig. 5 is an elevational view of one side of the release mechanism of my invention;

Fig. 6 is a view similar to Fig. 5 showing the other side thereof with certain parts removed for clearness of illustration;

Fig. 7 is a sectional view taken substantially on the line 7—7 of Fig. 5, showing a coin lever in its normal position locking a coin slide in fixed position;

Fig. 7A is a similar view showing the coin lever in the release position;

Fig. 8 is a sectional view taken substantially on the line 8—8 of Fig. 5, showing another coin lever in its normal or locking position;

Fig. 8A is a similar view showing the later coin lever in the release position;

Fig. 9 is a sectional view taken substantially on the line 9—9 of Fig. 5, showing a third coin lever in its normal or locked position;

Fig. 9A is a similar view showing said third coin lever in the release position;

Fig. 10 is a sectional view taken on the line 10—10 of Fig. 5 to bring out details of the coin slide and to show means for moving the coin levers to release position;

Fig. 11 is an enlarged fragmentary sectional view showing certain details of a shift bar adapted to move one of the coin levers of the release mechanism to release position in the absence of a coin normally required to release said lever;

Fig. 11A is a view similar to Fig. 11 showing the shift bar moved to a position in which the coin lever is moved to said release position;

Fig. 12 is a front elevational view of the release mechanism and change-maker mounted upon a frame provided therefor within the vending machine;

Fig. 13 is an enlarged view similar to Fig. 12, showing details of the release mechanism as well as means for transferring coins therefrom to change supply tubes;

Fig. 14 is an elevational view of the release mechanism with parts removed to better show the construction 60 of the coin slide and to show the position which coins will take therein when said coin slide is in its normal or locked position;

Fig. 14A is a view similar to Fig. 14 showing the coin slide moved to its release position;

Fig. 15 is an elevational view of the coin release mechanism and the associated change-making mechanism showing the arrangement of levers therebetween;

Fig. 16 is a view similar to Fig. 15 showing certain 70 of said levers removed and bringing out details of the change-making mechanism;

Fig. 17 is a partial elevational view of the lower por-

tion of a plate comprising the body portion of my release mechanism;

Fig. 18 is an end view of that portion of the plate shown in Fig. 17;

Fig. 19 is a fragmentary elevational sectional view of the vending machine of Fig. 1 showing the appearance of the inside of an end thereof;

Fig. 20 is a detailed plan view of a coin lever-raising plate for moving the coin levers to release position;

Fig. 21 is a detailed plan view of a portion of the lever arrangement interconnecting the release mechanism and the change-making device;

Fig. 22 is a detailed plan view of still another portion of said lever arrangement;

Fig. 23 is a fragmentary sectional view taken on the line 23—23 of Fig. 16;

Fig. 24 is a detailed plan view of one of the coin levers;

Fig. 25 is a fragmentary detailed plan view of a coin bucket actuating mechanism for transferring coins from said release mechanism to said change-making device;

Fig. 26 is a detailed plan view of still another of the coin levers;

Fig. 27 is an enlarged sectional view taken on a vertical plane showing details of the change-making mechanism;

Fig. 28 is a sectional view taken on the line 28—28 of Fig. 14;

Fig. 29 is a sectional view taken on a horizontal plane through a penny change mechanism; and

Fig. 30 is a sectional view taken on the line 30—30 of Fig. 29.

Referring now in detail to the drawings, 10 designates a vending device embodying the invention. The same comprises an outer casing 11 which includes a front wall 12, side walls 13, a rear wall 14, a top wall 15, and a bottom wall 16, the latter of which is shown in Fig. 12. The front wall 12 is provided with a pair of outlet receptacles 17 and 18 (Fig. 1) disposed on the left and right-hand sides of a lower portion of the wall.

Extending upwardly from the bottom wall 16, and spaced inwardly of and parallel to the side walls 13 of the casing 11, are a pair of vertical supporting plates 19 and 20 (Figs. 3 and 12). The plates 19 and 20 have horizontal flange portions 19a and 20a extending from the top edges of the plates and disposed toward each other.

Extending upwardly from a central portion of the bottom wall 16 of the casing 11 are a pair of similar, spaced, vertical central supporting plates 24 and 25 (Fig. 12) parallel to the end plates 19 and 20 and equally spaced on either side of the mid-section of the bottom plate 16. The plates 24 and 25 have flange portions 24a and 25a on the upper edges thereof coplanar with the flanges 19a and 20a on the plates 19 and 20 (Figs. 3 and 15). The plates 24 and 25 are formed with arcuate slots 26 therein (Fig. 15) horizontally opposite similar slots (not shown) in the end plates 19 and 20.

A horizontally disposed rectangular assembly plate 28 is supported upon the flanged upper edges 19a and 20a of the end plates 19 and 20 and the flanged upper edges 24a and 25a of the central plates 24 and 25, said plate being secured thereto by screws or the like (Figs. 3 and 15). The plate 28 is of a lesser width than that of the supporting plates and its forward edge is substantially coextensive with the forward edges of said supporting plates, thereby providing an open space 29 to the rear of the plate 28 (Fig. 3). Said plate 28 comprises a flange portion 30, extending upwardly from its forward longitudinal edge, and a flange portion 31 extending downwardly from its rearward longitudinal edge and received in suitable slots provided in the plates 24 and 25 (Fig. 15). The flange 30 is formed with a plurality of laterally spaced, channel shaped through openings 32 (Fig. 4) which comprise two groups, one of said groups being disposed on either side of the mid-section of the flange.

The flange portion 31 comprises lower end portions 33 spaced from each other by a centrally located portion 34 defined by notches 35 cut into the lower edge of the flange on either side thereof (Figs. 12, 13 and 15). The lower edge of the portion 34 is inclined forwardly and downwardly for reasons hereinafter appearing.

The plate 28 is formed with groups of laterally spaced, similar elongated slots 36 transversely disposed on either side of the mid-section of the plate (Fig. 3). Said slots 36 extend rearwardly to the rear edge of the plate 28 and have enlarged forward portions 37 disposed rearwardly of the front edge of the plate. The plate 28 is also provided with slots 38a which have rounded forward edges and are disposed in front of the slots 38 (Fig. 4). The plate 28 is provided with rectangular shaped slots 38 disposed between the elongated slots 36 and rearwardly of the enlarged portions 37 thereof.

The mid-section of the plate 28 is provided with a row of spaced, aligned rectangular slots 39, 40, 41 and 42 disposed rearwardly of the front edge of the plate and extending to the rear edge thereof. Said plate 28 is further provided with a narrow elongated slot 43 disposed to the left of the slots 39, 40, 41 and 42, and rearwardly of the front edge of the plate as seen in Fig. 3. The slot 43 extends to the rear edge of the plate 28.

A supplementary assembly plate 44 is disposed on the upper edges of the rear portions of the central supporting plates 24 and 25, being secured thereto by screws or the like. The plate 44 has a flange portion 45 on the front edge thereof extending downwardly into suitable slots in the plates 24 and 25 and in abutting relation with the upper portion of the rear flange 31 of the plate 28 (Fig. 15). The plate 44 may also have a flange portion 46 extending upwardly from the rear edge thereof. Said plate 44 is provided with a pair of aligned slots 47 and 48 extending rearwardly from the forward edge of the plate, said slots being disposed in alignment with the slots 39, 40, 41 and 42 in the plate 28 (Fig. 3). The plate 44 is further provided with a square slot 49 disposed between the left edge of the plate and the slot 47, as shown in Fig. 3.

The device 10 is provided with means for holding merchandise to be vended. To this end two groups of main chutes 50 and 51, which may, for example, comprise four chutes in each group, are disposed in spaced relation on the plate 28 leaving a central space therebetween as shown in Fig. 2. The chutes 50 and 51 are adapted to hold vertical columns of articles 52 which may be dispensed from rear outlets 50a in the chutes 50 (Fig. 19). The slots 38 in the plate 28 are adapted to receive lugs (not shown) on the lower ends of the chutes, for removably securing said chutes to the plate.

The chutes 50 and 51 may be provided with package guards 50b pivotally mounted, at the upper ends thereof to the rear walls of said chutes (Fig. 19). The lower ends of the guards 50b cover the rear outlets 50a of the chutes.

Reserve chutes 53 and 54 are also mounted on the plate 28, said chutes being disposed in the rear of the chutes 50 and 51 (Fig. 2). The reserve chutes are adapted to contain articles 52 which may be transferred to the main chutes 50 and 51 when the latter chutes are emptied. Groups of chutes 55 and 56 are also mounted on the plate 28 in front of the chutes 50 and 51 and are adapted to hold auxiliary articles 57 (Fig. 19) which may be dispensed simultaneously with the articles 52 by reciprocating dispensing means 58 (Fig. 4) in a manner more fully described in my copending application, Ser. No. 670,136, filed May 16, 1946, now Patent No. 2,522,316.

Each dispensing means 58 generally comprises a bar 59 slidably mounted on the plate 28 above one of the slots 36 in said plate. Each bar 59 comprises an article 75 supporting surface 60 disposed above the plate 28 and

adapted to underlie one of the main chutes 50 or 51 when the bar is in its normal position. Each bar 59 further comprises a vertical hook portion 61 disposed below the plate 28 (Fig. 12). Each bar 59 also has secured thereto, as by screws 62a, a pusher plate 62 which is disposed in front of the article supporting surface 60 and is adapted to move auxiliary articles 57 from the chutes 55 and 56 in the manner described in applicant's aforesaid copending application. An elongated channel shaped member 63 is secured to the forward end of each bar 59, the rear end of said member being disposed under the pusher 62. The channel shaped member 63 extends forwardly through the channel shaped openings 32 in the flange 30 of the plate 28 and through registering openings 64 in the front wall 12 of the casing 11 (Fig. 1). Operating handles 65 may be mounted on the projecting ends of the channel shaped members 63.

It will be understood that when a dispensing bar 59 is drawn forwardly, an article 52 from within the chutes 50 or 51, together with an auxiliary article 57 from the chute 55 or 56, will be disposed with respect to the bar 59 so as to permit dispensing of the same upon rearward movement of the bar 59 in a manner described in detail in applicant's above identified copending application. The articles 52 and 57 may drop to the rear of plate 28 into chutes not shown which may conduct said articles to the receptacles 17 or 18 from which they may be removed by a customer.

Provision is made for returning the dispensing means 58 to its normal retracted position after the bar 59 has been pulled forward. To this end, there is fixed to the end support walls 19 and 20 reinforcing brackets 66 which have openings therein (not shown) in which headed studs 68 are journaled and retained by cotter pins 69 (Figs. 3 and 19). Fixed to the studs 68 are arms 70 which carry at their outer ends a transverse horizontal operating rod 71. The rod 71 comprises reduced end portions 72 (Fig. 3) which project through arcuate slots in the plates 19 and 20 and project outwardly therefrom. Coil tension springs 73 are secured at one of their ends to the ends of the rod 71 and at their other ends to brackets 74 secured to rear portions of the walls 19 and 20. The hook portions 61 of the bars 59 engage the transverse rod 71 in a manner well-known in the art. It will be understood that forward movement of a bar 59 will bring the transverse rod 71 forward, thereby stretching the springs 73. Upon releasing the bar 59, the springs 73 will return the rod 71 and the engaged bar to their respective retracted positions.

Also mounted on the plate 28 may be penny change dispensing mechanisms 75 (Fig. 4) of the type more fully described in my copending application, Ser. No. 670,135, filed May 16, 1946, now Patent No. 2,457,187. For a purpose hereinafter appearing, the change mechanisms 75 may be disposed between the slidable channel shaped members 63.

The mechanism 75 essentially comprises a support 76 slotted on its undersurface and secured to the plate 28. The slotted portion of the support communicates at its rear end with the opening 38a in plate 28 and a vertically adjustable coin tube 77 is mounted on the front portion of the support with its lower end communicating with the front end of said slotted portion. A reciprocal slide 78 (Figs. 29 and 30) may be mounted in the slotted portion of the support 76 and may be actuated in a suitable manner by the reciprocal movement of the bar 59. The slide 78 is provided with an opening (not shown) which is adapted to receive a coin from the tube 77 when the slide is in its forward position.

A suitable arrangement for moving the slide may comprise a slidable member 79 disposed to one side of the support 76. The member 79 may have an upturned lug 79a (Fig. 29) at its forward end which is adapted to

engage a suitable projecting portion of the slide 78 and, further, may have an upturned lug 79b at its rearward end which may be engaged by an abutment 59a provided on the dispensing bar 59. An abutment 59b on the rear end of the dispensing bar 59 may also be provided to engage the lug 79b upon forward movement of the bar. It will be understood that, with this arrangement, upon retracted movement of the bar 59, the abutment 59a will engage the lug 79b on the slide 79, moving it rearwardly to a position where the coin opening in the slide 78 will register with the opening 38a in the plate 28 and thereby permit the coin to drop through said opening and to pass through suitable chutes (not shown) to the return receptacle 17 or 18. The number of coins dispensed from tube 77, upon movement of the bar 59, may be determined by moving the tube vertically to selected positions, spacing the bottom end of the tube above the plate 28 by the thickness of one, two, three or four coins. Additionally, slides having a central portion of a thickness equivalent to that of the plurality of coins to be dispensed, may be used in lieu of the slide 78.

Means may be provided to prevent a dispensing bar 59 from being retracted unless it is pulled forwardly to its fullest extent. The same may include a pivoted pawl 80 (Fig. 4) mounted on a plate 80a of the penny change mechanism 75. The pawl may be connected to a suitable lug on the plate by a coil spring 81. On the dispensing bar may be provided a longitudinal rack portion 82 which will rotate the pawl in a clockwise direction when the dispensing bar is pulled. If the dispensing bar is not drawn to its fullest extent, the pawl will prevent the bar from being retracted. However, when the rack 82 has fully passed the pawl 80, said pawl will be swung, by the spring 81, in a counterclockwise direction, and the dispensing bar can then be retracted.

Means may also be provided to permit only a single dispensing bar to be operated at any one time. To this end floating lock plates 83 (Fig. 4) may be slidably mounted under the members 79 of all the penny change mechanisms 75 except the two immediately adjacent the mid-section at the plate 28. The plates 83 may have diagonally cut corners 84 extending from the rear edges thereof and said rear edges may be provided with recesses 85 disposed intermediate the diagonal corners 84. The plates 83 are in side edge abutting relationship but are adapted to move laterally. The movement of the plates 83 may be limited by means of upstanding lugs 86 on the rear edges of the change mechanisms and disposed in the recess 85 of the plates. The abutting side edges of the plates 83 may be disposed in the path of the bars 59 and the total clearance between all the locking plates may be sufficient to permit only one bar 59 to pass between a pair of plates. Upon forward movement of a selected bar 59, as shown in Fig. 4, the plates 83 will be moved apart by the forward edge of the bar and as a result, the plates 83 to the right of the separated plates, will be brought into abutting relationship. The position of the plates prevent forward movement of the bars 59, other than the selected bar, since the forward edges of said bars will be stopped by the diagonal edge portions of the abutting plates. Dispensing bars 59 on the left-hand side of the device may also be locked against forward movement by means of lock plates 87 which may be disposed on the penny change mechanisms 75 immediately adjacent the mid-section of the plate 28. The plates 87 disposed adjacent the mid-section may be formed with diagonal corners 84 on one side and the other sides interconnected by an integral link portion 88 extending across the mid-section. It will be readily understood that lateral movement of the plates 83 on one side of the device, occasioned by the movement of one dispensing bar, will be transmitted to the other side of the device to produce a locking action in a manner similar to that previously described.

Means may be provided for preventing articles from being improperly removed from the rear outlets 50a of the chutes 50 and 51 while a dispensing bar 59 is in its forward position. To this end, rocker rods 89 may be journaled in suitable openings in the end plates 19 and 20 and in openings aligned therewith in the center plates 24 and 25 (Figs. 3 and 19). Extending upwardly from the rods 89 may be spaced L shaped plates 90 disposed in an inverted position opposite the rear outlets in the chutes 50 and 51. Each end of the rods 89 projecting from the end plates 19 and 20 may comprise an upwardly extending portion 91 and an outwardly extending portion 92 thereon. The outwardly extending portions 92 of the rods 89 and the end portions of the transverse rod 71 may be interconnected by offset arms 93 suitably secured thereon by means of cotter pins. Upon forward movement of the dispensing bar 59 and the transverse rod 71, pivoted movement will be imparted to rods 89 through the arms 93, which will bring the horizontal portion of the plates 90 into a position preventing outward movement of the pivoted package guard 50b which covers the outlets 50a of the chutes 50 and 51, as shown by the full lines in Fig. 19. This will prevent tampering with the contents of the chutes while a dispensing bar 59 is in its forward position since the package guard 50b in its restricted position will bar access to the chute outlets.

Means are provided for locking the dispensing bars 59 against movement and for releasing said bars for movement upon the insertion of a proper coin or coins into the device. To this end a coin controlled release mechanism 94 is mounted transversely on the mid-section of the plate 28 between the groups of chutes 50 and 51 (Figs. 12 and 13). The mechanism generally comprises an upstanding body plate 95, a coin slide 96 slidably mounted on a lower portion of the body plate, and a cover plate 97 disposed over one surface of the body plate and screwed thereto.

The body plate 95 illustrated in the drawings is of irregular outline and has opposite side surfaces 95a and 95b, as shown in Figs. 5 and 6. The plate 95 comprises a right-hand side edge 98, from the lower end of which extends an inwardly and downwardly inclined edge 99. A vertical side edge 100 extends from the edge 99 and a horizontally disposed edge 101 extends from the edge 100. Extending from the edge 101 is a vertical edge 102. The plate 95 further comprises a bottom edge 103 from which a horizontally disposed mounting flange 104 projects from the back surface 95b (Fig. 10). From the bottom edge 103 there extends a short vertical side edge 105 with a horizontal edge 106 extending inwardly therefrom. A short vertical edge 107 extends from the edge 106 and continues as an outwardly curved and upwardly extending edge 108. From the edge 108, there extends a vertical edge 109 from which extends successively set-back vertical edges 110 and 111.

The plate 95 further comprises a horizontally extending flange 112 which projects outwardly of the face 95a from the edge 101 as shown in Figs. 6 and 17. A post 113 formed with a threaded bore 114 extends outwardly of the inner end of the flange 112 adjacent the edge 103 (Figs. 17 and 18). The surface 95a of plate 95 has a boss 115 projecting therefrom, which is formed with a threaded opening 116. The boss 115 is disposed adjacent the edge 102 and is spaced above the bottom edge 103. The plate 95 also includes a plurality of bosses 117, 118, and 119 disposed along its lower portion in spaced relation on the face 95a, the outer faces and upper edges of said bosses being coplanar with the corresponding face and upper edge of the boss 115. Said bosses 117, 118, and 119 extend to the bottom edge 103 of the plate and are provided with threaded openings 120, 121 and 122, respectively, which are in horizontal alignment with the threaded opening 116 in the boss 115. The plate 95 further includes a series of short horizontally spaced ribs

123, 124, and 125 projecting from the face 95a and extending vertically from the bottom edge 103 of the plate. The space between the bosses 115 and 117 forms a vertical passageway 125a, and the rib 123, being disposed between the bosses 117 and 118, forms a pair of vertically extending passageways 126 and 127. Similarly, the rib 124 is disposed between the bosses 118 and 119 forming a pair of vertically extending passageways 128 and 129 while the rib 125 is disposed between the boss 119 and the edge 105, thereby forming a passageway 130 disposed to the right of rib 125, as best shown in Fig. 17. The lower ends of passageways 125a, 126, 127, 128, 129 and 130 on the plate 95 communicate with the slots 39, 40, 41, 42, 47 and 48, respectively, in plates 28 and 44.

A horizontal flange 131 projects outwardly from the upper end of the rib 125 and extends to the edge 105. The upper edge of said flange is at a level slightly below the upper edge of the boss 119.

The face 95a of the plate 95 is provided on its lower portion with a recessed surface 132 (Fig. 17) adapted to accommodate the coin slide 96. The lower limits of the recess is defined by the upper edges of the bosses 115, 117, 118 and 119 and the flange 131, while the upper limits of the recess is defined by a horizontal flange 133 disposed along the edge 106 parallel with the flange 131 and extending inwardly from the edge 105.

A rectangular boss 134 having its lower edge coplanar with the lower edge of the flange 133 is disposed in spaced relation to the inner end of the flange 133, thereby forming a vertically extending passageway 135 having its lower wall slightly raised with respect to the face of the recess 132.

The upper limits of the recess 132 are further defined by a raised portion of the face 95a of the plate 95 which is bounded by a lower horizontal edge 136 extending from the upper edge of the boss 134, a vertical edge 137 extending from the inner end of the edge 136, and by a horizontal edge 138 extending from the upper end of the edge 137. Said edge 138 extends to the plate edge 102 and, at its outer end, defines the lower edge of the flange 112. Extending upwardly from the edge 136 and disposed between the edge 137 and the boss 134 is a recessed portion forming a passageway 139 which has an inner wall having a lower portion substantially coplanar with that of the passageway 135. Similarly, a recessed portion forming an upwardly extending passageway 140 extends from the edge 138, said passageway being disposed between the edge 137 and the inner end of the flange 112.

The recessed surface 132 of the plate 95 is provided with a plurality of vertically spaced, horizontal, parallel slots 141, 142, 143, 144 and 145 which are disposed inwardly of edge 102 (Fig. 17). Said recessed surface is also provided with a plurality of vertically spaced, horizontal, parallel slots 146, 147, 148 and 149 which are disposed above the boss 117 and are in horizontal alignment with the slots 141, 142, 143 and 144, respectively. The recessed surface is further provided with a pair of horizontal, vertically spaced, parallel slots 150 and 151 which are disposed above the boss 118. A horizontal slot 152 is provided in the recessed surface between the slots 150 and 151, a horizontal slot 153 disposed above the boss 119, and an elongated horizontal slot 154, which extends along the upper edge of the flange 131, is provided between the boss 119 and the plate edge 105.

The upper portion of the surface 95a of plate 95 is provided with a plurality of tortuous pathways along which nickels, dimes and quarters, inserted into the coin release mechanism, may move. To this end, the surface 95a has formed thereon spaced tortuous ribs 155, 156, 157, and 158 which define therebetween a quarter path 160, a dime path 161, and a nickel path 162 (Fig. 6). The lower end of the path 160 communicates with the passageway 135, the path 161 communicates with the passageway 139, and the path 162 communicates with

passageway 140. Magnets 162a (Fig. 5) are mounted in openings 162b in the plate 95 in the lower portion of the paths 160, 161 and 162, the faces of said magnets being flush with the surfaces of the paths. The pathways 160, 161 and 162 extend at their upper ends to the edge 98 of the plate 95, the edge 98 being disposed adjacent the inner surface of the front wall 12 of the casing 11. The wall 12 is provided with the usual coin openings, not shown, registering with the entry portions of the coin pathways, thereby permitting the insertion of coins 10 into the proper openings.

The surface 95a of the plate 95 is also provided with a pocketed portion 163 disposed adjacent the lower end of the path 162 for receiving counterfeit coins or slugs which are deflected from their normal path by the magnets. Similarly, a second pocketed portion 164 is disposed below the pocketed portion 163 adjacent the lower end of the path 161 and is adapted to receive deflective counterfeit coins from the path 161. A third pocketed portion 165 is disposed adjacent the lower end of the path 160 for receiving deflected coins therefrom.

Provision may be made for detecting and segregating oversize, undersize, and underweight coins, slugs, and the like by means of a coin selector, shown generally by the numeral 166 in Fig. 6, which may be disposed in the upper ends of the paths 160, 161 and 162. The coin selector indicated generally at 166 is fully described in applicant's application Ser. No. 18,443, filed April 1, 1948, now Patent No. 2,632,547.

The coin slide 96, which is horizontally slidably mounted in the recessed surface 132 of plate 95, is of a shape generally conforming to the outline of said recess. Said slide comprises a horizontal bottom edge 167 from which extends a right-hand vertical edge 168, looking at Fig. 14A. A top horizontal edge 169, parallel to the bottom edge 167, extends from the edge 168 inwardly, and a vertical edge 170, parallel to edge 168, extends downwardly therefrom. A horizontal edge 171, parallel to the bottom edge 167, extends from the edge 170 and is terminated in a raised portion 171a. A short vertical edge 172 extends downwardly from the edge 171, from the latter of which extends a horizontal edge 173 parallel to the bottom edge 167 and terminating in a raised portion 173a. Said edge portion 173a extends to a left-hand vertical edge 174 of the slide 96.

The horizontal edges 171 and 173 of the slide are provided with shallow elongated recesses 175 and 176, respectively. When said slide 96 is mounted in the recess 132 of the plate 95, the top edge 169 is disposed adjacent the edge 138 of the plate 95, the edge 171 is disposed adjacent the edge 136, and the edge 173 is disposed against the lower edge of the flange 133. The bottom edge 167 is slidably disposed on the upper edges of the bosses 115, 117, 118 and 119 provided on surface 95a of the plate 95. The outer vertical edge of the boss 134 acts as a stop for the edge 172 of the slide, and similarly, the edge 137 acts as a stop for the edge 170 when said slide is in its retracted position.

The slide 96 is provided with a plurality of vertically spaced horizontal through slots 177, 178, 179 and 180 spaced inwardly from the edge 168 and adapted to register with the slots 141, 142, 143 and 144, respectively, in the body plate 95 when said slide is in its forward position, as shown in Fig. 14A. When the slide 96 is in its retracted position, as shown in Fig. 14, the slots 177, 178, 179 and 180 register with the slots 146, 147, 148 and 149, respectively. The slots 177, 178, 179 and 180 are provided with undercut portions 181 therein extending from the ends of the slots toward the edge 170. The slide 96 is also provided with an elongated horizontal through slot 182 disposed immediately above the bottom edge 167 and adjacent the inner end of the slot 180. A similar horizontal through slot 183 is formed in the slide below the recess 175 and in parallel relationship with the slot 182. The slots 182 and 183 are also provided with

undercut portions 184 on the rear surface of the slide 96 extending toward the edge 174 and adapted to register with the slots 150 and 151 in the plate 95. The slide 96 also comprises an elongated rib 185 extending outwardly therefrom and disposed immediately below the recess 175 in the edge 171 of the slide.

The under surface of the slide 96 is provided with an elongated, horizontal slot 186 disposed between the slots 182 and 183 and adapted to register with the slot 152 in the plate 95. Said slide is also formed with an elongated horizontal through slot 187 disposed between the bottom edge 167 and the recess 176 in the edge 173 of the slide. Said slot 187 is provided with an undercut portion 188 on the under surface of the slide 96 extending toward the edge 174 and is adapted to register with the slot 153 in the plate 95. The slide 96 further comprises a projecting post 189 having therein a threaded bore 189a, said post being disposed adjacent the edges 167 and 174 of said slide. An L-shaped member 190 is secured to the edge 168 of the slide 96, as by screws 191, and a bracket 192 is secured to the outer face of the slide opposite the slot 178 and projecting beyond the edge 168. Said bracket includes an outwardly projecting apertured lug 193 disposed on the outer end thereof.

The slide 96 has provided therethrough transverse, spaced, vertical coin slots 194, 195 and 196 which extend upwardly from the edge 167 thereof, as is best shown in Figs. 7, 8 and 9. The slot 194, which in the embodiment shown is of such dimensions as to freely pass a nickel, intersects the slots 177, 178, 179 and 180 and is adapted to receive four vertically disposed nickels, as shown in Fig. 14. The slot 195, which in the present embodiment will freely pass a dime, intersects the slots 182 and 183 and extends to the recess 175 and is adapted to retain two vertically disposed dimes. The slot 196, which may be of such dimensions as to freely pass a quarter, intersects the slot 187, extends to the recess 176, and is adapted to receive a single coin, as is shown in Fig. 14.

When the slide 96 is in its retracted position, the slot 194 communicates at its upper end with the passageway 140 in the plate 95 and at its lower end with the passageway 126. When the slide is in said retracted position, the slot 195 communicates at its upper end with the passageway 139 in the plate 95 and at its lower end with the passageway 128, while the slot 196 communicates at its upper end with the passageway 135 and at its lower end with the passageway 130. On the other hand, when the slide 96 is in its forward position, the slot 194 communicates at its lower end with the passageway 125a, the slot 195 communicates at its lower end with the passageway 127, and the slot 196 communicates at its lower end with the passageway 129.

The cover plate 97, which overlies the surface 95a of body plate 95 (Fig. 6) converts the pathways 160, 161 and 162 into coin slots through which quarters, dimes and nickels may pass, respectively, to the release mechanism. Said cover plate is of irregular outline having side edges conforming to the edges 100, 106, 107, 108, 109 and 110 of the plate 95, and also comprises stepped upper edge portions 201 which abut portions of the coin selector 166. Keepers 201a are mounted in openings in plate 97 with their inner faces flush with the inner face of the plate and disposed opposite the magnets 162a. The plate 97 is provided with an opening 202 which communicates with the adjacent pocketed portions 163 and 164 of the plate 95 and with an opening 203 which communicates with the pocketed portion 165 of the plate 95.

An outwardly projecting shelflike bracket 204 is secured to the lower edge portions of the plate 97 (Fig. 14A). Said bracket 204 comprises a horizontal portion 205 extending from the edge 105 across the lower inner edge of the opening 203. The horizontal portion 205 has extending downwardly from the inner edge thereof a vertically disposed flange 206 which overlies the upper edge

173 of the slide 96, thereby retaining the rear portion of the slide plate during its sliding movement. From the bracket portion 205 there extends a vertical portion 207 disposed opposite the inner vertical side of the opening 203 and a vertical portion 208 disposed opposite the outer vertical side of the opening 203, thereby defining a short downwardly inclined chute 209 communicating with the opening 203. From the upper end of the vertical portion 207 there extends a horizontally disposed portion 210 having a horizontal under surface 211 (Fig. 16). From said portion 207 there also extends an upwardly inclined surface 212. A vertically disposed flange 213 extends from the inner side of the portion 210 and overlies the outer face of the slide 96 adjacent the edge 170. A vertical strip 214 extends from the end of the inclined surface 212 along the right-hand vertical edge of the opening 202. Said strip 214 and the inclined surface portion 212 form a guide for coins issuing from the opening 202, thereby conducting them to the chute 209.

A vertically disposed plate 215 extends outwardly from the strip 214, overlapping the right-hand portion of the bottom edge of the plate 97 and the upper edge 169 of the coin slide 96, thereby retaining the front portion of the slide during its sliding movement. The plate 215 is provided with a horizontal slot 216 and a projecting lug 217, the latter of which is disposed immediately above said slot which registers with the edge 138 (see Fig. 17 and Fig. 28) of plate 95. A lever 218 is pivotally mounted on the underside of the lug 217 and has an arm which is disposed in the slot 216 and another arm which is connected to the strip 214 by a coil tension spring 218a (Fig. 16). When the slide 96 is in its retracted position, the end of the inner arm of the lever 218 disposed in slot 216 rests on the outer face of the slide. Upon forward movement of the slide, the arm is free to move inwardly due to the tension of the spring 218a. Accordingly, the arm will move through the slot 216 to a position shutting off the lower end of passageway 140 (refer to Fig. 17), for a purpose hereinafter described.

Slidably mounted on the under surface of the portion 205 of the bracket 204 is an elongated push bar 219 (Fig. 16 and Fig. 23). Said push bar is retained in slidable contact with the under surface of the portion 205 by means of a member 220 comprising an offset flange portion 221 secured to the portion 205 as by screws 222. The push bar 219 also comprises, at its outer end, a downwardly turned flange 223 provided with a transverse threaded opening 224 (Fig. 22). Mounted transversely on the under surface of the bar 219 and projecting into the recess 176 on the slide 96 is a lug 225. Similarly, a short push bar 226 (Fig. 15) is slidably mounted on the under surface 211 of the bracket portion 210 by means of a member 227 having an offset portion 228 secured to the under surface 211 as by screws 229. The push bar 226 also comprises, at its forward end, a downwardly extending flange 230 provided with a transverse threaded opening 231 (Fig. 21). Mounted transversely on the under surface of bar 226 is a lug 232 (Fig. 16) which projects into the recess 175 on the slide 96.

The cover plate 97 is also provided with an opening 233 (Fig. 6) which is disposed opposite the lower end of the rib 155 on the plate 95 at the upper end of the passageway 135 (refer to Fig. 17) and an opening 234 which is disposed between the upper end of the opening 203 and the left-hand side of the opening 202. A coin deflecting lever 235, serving a purpose hereinafter described, is pivotally mounted on the plate 97 and has an inwardly turned lug 236 on one arm thereof projecting into the opening 233. The other arm of the lever 235 comprises an outwardly turned lug 237. There is also provided another lever 238, similar to the lever 235, which is pivotally mounted on the plate 97 and has provided thereon an inwardly turned lug 239 on an arm projecting into the opening 234. The other arm of the lever 238 comprises an outwardly turned lug 240. The plate 97 is

also provided with adjustable deflector members 241 and 242 which project into the openings 202 and 203, respectively. An adjustable deflector member 243 is also mounted on the plate 97 and projects into a slot 244 cut into said plate.

For the purpose of retaining the lower edge of the slide 96 during its sliding movement, there is provided an elongated slide holder, shown generally at 245, which is secured to the bosses 115, 117, 118 and 119 on the plate 95 (Fig. 14). The holder 245 is provided with a pair of spaced elongated notched portions 246 and 247 along its upper edge which is defined by projections 248, 249 and 250 which overlay the bottom edge 167 of the slide 96. The holder 245 is secured to the bosses 115 and 117 by screws 251 which are received in the threaded openings 116 and 120, respectively, thereof. A stud 252, having a threaded end portion, passes through a transverse opening (not shown) in the holder 245 and is received in the threaded opening 121 of the boss 118. A similar stud 253 passes through a transverse opening (also not shown) in the holder 245 and is received in the threaded opening 122 in the boss 119. An elongated coin return bar, shown generally at 254, is slidably mounted on the outer surface of the holder 245. Said bar 254 (Fig. 16) is provided with a pair of spaced elongated slots 255 and 256 therein which are engaged by the studs 252 and 253 on the holder 245. The rear end of the bar 254 is provided with a lug 257 which is interconnected to an anchor member 258, mounted on the stud 253, by a coiled tension spring 259. The bar 254 also comprises spaced lug portions 260 and 261 (Fig. 14), which extend at right angles to the bar through notched portions 246 and 247, respectively, of the holder 245, and project over the upper ends of the passageways 126 and 128 on the plate 95, respectively. A third lug 262 (Fig. 14) extends inwardly from the rear end of bar 254 and projects over the upper end of the passageway 130 in the plate 95 (see Fig. 17). When the slide 96 is in its retracted position, the lugs 260, 261 and 262 are disposed under the lower ends of the slots 194, 195 and 196, respectively, in the slide. From the upper edge of the bar 254, there extends an upstanding lug 263 which is formed with a transverse threaded opening 264 (Fig. 16).

The back surface 95b of plate 95 comprises an outwardly projecting horizontal lug 265, disposed adjacent the edge 105 of the plate, and provided with a vertical transverse opening therethrough (Fig. 5).

A pair of upstanding, parallel guide lugs 266 are disposed on either side of the slot 153 in the plate 95. A pair of vertically aligned rod holding supports 267 and 267a are disposed in vertically spaced relation on the surface 95b of the plate 95 (Fig. 17) and have provided therein aligned grooves 268. Cover members 269 (Fig. 5), covering the upper portion of the grooves 268, are fixed to the tops of the supports 267 as by screws. Disposed between the supports 267 and 267a are vertically spaced, upstanding grooved lever spacing lugs 271, 272 and 273 which are in alignment with the grooves 268 in the supports 267. An upstanding lug 274 (Fig. 5 and Fig. 10) is disposed adjacent the slot 152 with a coin separating member 275 (Fig. 9) secured thereto. The member 275 comprises an end portion projecting through the slot 152 and received in the slot 186 in the slide 96.

Pairs of upstanding horizontal guide lugs 276 are disposed on either side of each of the slots 146, 147, 148 and 149 (Fig. 5 and Fig. 17). An upstanding lug 277 is disposed between the lowermost pair of the guide lugs 276 and the flange 104 of the plate. A pair of aligned pin holding supports 278 and 278a, similar to the supports 267 and 267a, are disposed to the right of the guide lugs 276, as shown in Fig. 5. The supports 278 and 278a are also grooved and provided with cover members 269. Another set of aligned pin holding supports 279 and 279a, similar to the supports 267 and 267a, are

disposed at opposite ends of the edge 102 of the plate. Upstanding bosses 280, 281 and 282 are disposed adjacent the guide lugs 276. Additional bosses 283, 284, 285 and 285a are disposed in horizontal alignment with the bosses 280, 281 and 282, respectively.

An upstanding post 286 provided with a threaded bore is disposed at the intersection of the edges 106 and 107 of the plate 95.

Means are provided for obstructing the movement of the slide 96 except upon the receipt of a predetermined number of coins within the slide. To this end there is mounted on the surface 95b of plate 95 a plurality of coin levers. The same comprise a set of four similar elongated nickel levers 1, 2, 3 and 4 which are disposed in parallel relationship and received at one end thereof between the spaces separating the upstanding lugs 271, 272 and 273 at their other ends between the guide lugs 276. Each nickel lever is substantially rectangular in shape and comprises an outer edge 288 (Fig. 9), a rounded rear edge 289, an inner edge 290, and a vertical front edge 291 having rounded corners. From the inner edge 290, and at the front end of each lever, there extends a shouldered projection 293 to provide a hook-like shape. Also extending inwardly from the edge 290 and spaced rearwardly of the projection 293 is a projection 294. The projection 293 comprises a short vertical edge 295 parallel to the edge 288 and extending rearwardly from the inner rounded corner of the edge 291, and a diagonal edge 296 extending from the edge 295. The projection 294 comprises an arcuate cam edge 297 extending from the edge 290 and an edge 298 (Fig. 9A), parallel to edge 291, extending inwardly therefrom. The bases of the projections 293 and 294 are interconnected by an edge 299 parallel to the edge 288 and offset with respect to the edge 290. The levers are provided with transverse threaded openings 300 adjacent the forward edge 291, a transverse threaded opening 301 adjacent the edge 288 and opposite projection 294, and a transverse opening 302 (Fig. 9) adjacent the rear edge 289.

There is also provided a pair of dime levers 5 and 6. The lever 5 comprises a rounded rear edge 304 (Fig. 26), an outer edge 305, a front edge 306 extending transversely of the edge 305, and an inner edge 307 parallel to the edge 305. A projection 308 extends outwardly from the forward portion of the edge 305 and comprises an outer edge 309 which is parallel to the edge 305 and extends to the edge 306. A projection 310 extends inwardly from the edge 307 and is disposed opposite the projection 308. The projection 310 comprises an arcuate edge 311, which extends from the edge 307, and a vertical edge 312 extending from the edge 311 and merging with the front edge 306. The dime lever 6 is similar to the lever 5 in all respects except that it comprises an outwardly extending projection 308a which is of smaller size than the projection 308 on the lever 5. The levers 5 and 6 are provided with transverse openings 313 therein disposed opposite the rear edge 304 thereof.

There is further provided a quarter lever 7 of a shape shown in Fig. 9. The lever 7 comprises a rounded rear edge 315, from which extends parallel edges 316 and 317, and a front edge 318. Extending from the front end of the lever, in offset relation to the edge 317, is a projection 319. The projection 319 comprises a horizontal edge 320 extended from the edge 317, a transverse front edge 321 (Fig. 9A), and an arcuate cam edge 322 extending therefrom to the edge 317. The lever 7 is formed with a transverse opening (not shown) disposed adjacent the rear edge 315.

An elongated extra lever 8 is provided for a purpose hereinafter appearing. Lever 8, the details of which are shown in Fig. 24, comprises a rounded rear edge 325 from which extends parallel outer and inner edges 326 and 327, and a front edge 328. A shouldered projection 329 extends downwardly from the front edge of the lever and comprises a short edge 330, parallel to the edge 326,

from which there extends an inclined edge 331. The lever 8 is provided with a transverse through opening 332 adjacent the rear edge 325, and is further provided with a transverse threaded opening 333 adjacent its front edge 328. The lever 8 is also provided with a transverse threaded opening 334 adjacent the outer edge 326 and disposed inwardly of the front edge 328.

A transverse pivot pin 335 (Fig. 5) is mounted in the grooves 268 of the supports 267 and 267a and extends through the grooves in the intermediate lugs 271, 272 and 273. The nickel levers 1, 2, 3 and 4 are pivotally mounted on the pin 335 which is received in the openings 302 in said levers. The levers are successively separated by the support 267, separating lugs 273, 272 and 271 and the supports 267a. It will be apparent, from consideration of Figs. 7 and 17, that with the slide 96 in its retracted position, the nickel levers 1, 2, 3 and 4 are disposed with their projections 293 extending through the slots 141, 142, 143 and 144, respectively, in the plate 95. Similarly, projections 294 on the nickel levers extend through the slots 146, 147, 148 and 149 in the plate 95 and project into the slots 177, 178, 179 and 180 of the slide 96. The dime lever 5 is also pivotally mounted on the pin 335 which is received in the transverse opening 313 thereof. Said lever 5 is disposed below the nickel lever 1 with the projection 310 thereon extending through the slot 151 in the plate 95 and projecting into the slot 182 of the slide 96. The dime lever 6, also pivotally mounted on the pin 335, is disposed below the nickel lever 2, with its projection 310 extending through the slot 151 in the plate 95 and projecting into the slot 183 of the slide 96.

The extra lever 8 is also pivotally mounted on the pin 335, which is received in the opening 332 thereof. The lever 8 is disposed below the dime lever 5 and extends between the lug 277 and the lowermost of the guide lugs 276. The projection 329 on the lever 8 is adapted to extend into the slot 145 in the plate 95. The quarter lever 7 is pivotally mounted on the lug 265, as by a pin 336, and extends between the guide lugs 266 and 266a, with the projection 319 on the lever extending through the slot 153 in the plate 95 and projecting into the slot 187 of the slide 96.

Means are provided for simultaneously rotating all the nickel levers as well as the extra lever 8. To this end there is provided a member 337 (see Figs. 5 and 9) which may be actuated by rotation of the quarter lever 7. The member 337 comprises an elongated portion 338 having at one end thereof an inwardly turned apertured flange 339 received on the pin 335 and disposed immediately below the pin support 267a. The portion 338 further comprises, on its upper end, an inwardly turned apertured flange 340 received on the pin 335 and disposed immediately above the pin support 267. Extending outwardly from the flange 340 is an apertured lug 341. The lower edge of the portion 338 of the member 337 is disposed over the horizontal edge 320 of the quarter lever 7, as shown in Fig. 9. A coin lever raiser 342, interconnected to the member 337, is disposed vertically adjacent the guide lugs 276. Said lever raiser 342 comprises a vertically disposed elongated portion 343 which underlies the nickel levers 1, 2, 3 and 4, and the extra lever 8. Extending from opposite ends of the portion 343 are ears 344 and 345 (Fig. 5), which are provided with apertures 346, said apertures being offset with respect to the portion 343, as is shown in Fig. 9A. The raiser 342 is pivotally mounted on pins 347 journaled on the supports 278 and 278a, and received in the apertures 346 in the ears 344 and 345. Extending outwardly from the ear 345 is an apertured lug 348 which is parallel to the lug 341 on the member 337 (Fig. 9). An elongated arm 349 pivotally interconnects the lugs 337 and 348 by means of screws 350 received in the apertures of said lugs. The arm 349 includes a transverse lug 351 extending from the inner end thereof. It will be apparent that, upon manually pulling the arm 349 forward by means of the lug 351, the interconnected raiser 342 will be pivoted into a posi-

tion in which the portion 343 will raise the nickel levers 1, 2, 3 and 4 and the extra lever 8, as shown in Fig. 9A.

The nickel levers 1, 2, 3 and 4 and the extra lever 8 are normally urged toward the surface 95b of the plate 95 by means of spring members 352, curved ends of which are retained as by screws 283 threaded into the plate 95. Arms of the spring members 352 pass under washers 353, retained on bosses 280, 281 and 282, and extend toward the nickel levers and the extra lever. The extremities of the spring arms are hooked over the outer edges of the coin levers as is shown in Fig. 5.

With the coin slide 96 in its retracted position, the slide is normally locked against forward movement by the nickel levers 1, 2, 3 and 4 and the extra lever 8 from which the projections 293 and 329 protrude through the slots 141, 142, 143, 144 and 145 in the plate 95. The inclined edge portions or shoulders 296 and 331 on the projections 293 and 329, respectively, are disposed opposite the vertical edge of the L shaped member 190 on the slide 96 in slightly spaced relation thereto permitting limited slidable movement of the slide, but are adapted to obstruct full forward movement of said slide. In order to permit the slide to be released for forward movement, the nickel levers 1, 2, 3 and 4, as well as the extra lever 8, must be rotated sufficiently so that projections 293 and 329 will no longer obstruct the L shaped member 190 on the slide 96. This may be accomplished directly or indirectly by a camming action of coins inserted into the device in a manner hereinafter described in detail.

Means are provided for selectively raising particular coin levers or combinations thereof. To this end, there is provided a channel shaped member 354 which is pivotally mounted on the pin 335 (Figs. 5 and 10). The member 354 comprises a rectangular vertically disposed top wall 355 having a width sufficient to extend over the extra lever 8 and the nickel levers 1, 2 and 3. Extending from the wall 355 are bottom and top walls 356 and 357 which are formed with aligned openings on their rear portions for receiving the pin 335. Extending from the inner edge of the wall 356 and adjacent the free end thereof is a short lug 359 which is disposed behind the extra lever 8 (Fig. 10). Similarly, a lug (not shown) projects outwardly from the free end of the upper wall 357 and is disposed beneath the nickel lever 4. The channel shaped member 354 is provided with a detachable angle bracket comprising an arm 365 (Figs. 5 and 7) which is secured to the wall 355 of the member by means of screws 366 received in threaded openings 363 in said wall. Extending from the arm 365 over the front edge of the wall 355, at right angles thereto, is an arm 367 from which extends a flange 368 (Fig. 10) parallel to the wall 355 and having projecting lugs 369 thereon which are substantially coplanar with the lug 359.

A second channel shaped member 370 is pivotally mounted on the pin 335 and is disposed interiorally of the member 354. The member 370 comprises a vertical outer wall 371 from which extends bottom and top walls 372 and 373 (Fig. 10) which are provided with aligned openings (not shown) on their rear portions for receiving the pin 335. A short lug 375 extends upwardly from the inner end of the top wall 373. An angle member is disposed within the member 370 and has a vertical wall 376 secured to the under surface of the wall 371 and a vertical wall 377 disposed in spaced parallel relation to the top wall 373. A short lug 378 extends downwardly from the inner edge of the wall 377 to a position beneath the lever 2. A second angular member 379 is removably secured to the inner surface of the wall 371 and comprises a vertical wall provided with threaded openings for receiving screws 381 which pass through the wall 371. Said vertical wall comprises a portion 382 (Fig. 5) projecting outwardly from the front edge of the top wall 371. A horizontal wall 383 (Fig. 10) extends from the vertical wall adjacent the

side wall 372 and is provided with a short lug 384 projecting from the inner edge thereof to a position beneath the lever 1. The channel shaped member 370 is mounted on the pivot pin 335 with the inner surface of the outer wall 371 in contact with the outer edge of the nickel lever 2 and the outer edge 309 of the dime lever 6.

As is shown in Fig. 10, the lug 375 on the member 370 is disposed under the inner edge of the nickel lever 3, the lug 378 is disposed under the inner edge of the nickel lever 2, and the lug 384 is disposed under the inner edge of the nickel lever 1. The channel shaped member 354 is also mounted on the pivot pin 335 with the inner surface of its outer wall in contact with the outermost edge of the dime lever 5. The lug 359 of the member 354 is disposed under the inner edge of the extra lever 8, and another lug, not shown, is disposed under the inner edge of the nickel lever 4. The projecting lugs 369 on the bracket 365 on the member 354 are disposed under the inner edges of the nickel levers 3 and 4.

Slidable movement is imparted to the slide 96 by interconnection of the same with the transverse rod 71. To this end there is provided an arm 385 which is pivotally mounted, at one end thereof, on the post 113 by means of a screw 386 received in the threaded bore 114 thereof (Fig. 6). The arm 385 is provided at its other end with a hook 386a which engages the rod 71, as is shown in Fig. 14. The arm 385 is pivotally interconnected to the slide 96 by an arm 387 which is pivotally mounted, at one end thereof, on the post 189 by a screw 388 received in the bore 189a in the post. The other end of the arm 387 is pivotally mounted on the arm 385, at a point above the hook 386, as by a pivot screw 389. It will thus be apparent that forward movement of a dispenser bar 59 will pull the rod 71 forward and will thereby produce forward movement of the slide 96. Said slide is urged toward its normal retracted position by means of a coil spring 390 which interconnects the lug 193 on the slide and an anchor member 391 mounted on the bracket 204 on the cover plate 97.

With a selected setting of the coin release mechanism, as more fully described hereinafter, the insertion of a coin or combination of coins into the mechanism is effective to permit forward movement of the coin slide simultaneously with the forward movement of the rod 71 and a selected dispensing bar 59.

Means are provided for vending articles from selected chutes of the device at a price different from that at which articles in the other chutes are vended. More particularly, the release mechanism is adapted to be operated upon the insertion of coins amounting to five cents less than the amount at which the release mechanism is adjusted. To this end, elongated operating bars 392 and 393 (Fig. 3) are slidably mounted in front of the penny change mechanisms 75. The bar 392 is disposed over front portions of the change mechanisms in the right-hand side of the cabinet and is retained by the guide brackets 394 screwed to the mechanisms. The bar 392 is provided with pairs of threaded openings 395 therein (Fig. 4) disposed on the bar opposite each of the change mechanisms except the innermost one, as is shown in Fig. 4. A short lug 396 extends upwardly from the inner end of the bar 392, the latter of which projects beyond the innermost right-hand change mechanism. The bar 392 is also provided with a short slot 397 disposed on the bar opposite the innermost change mechanism. Detachable angle members 398 are adapted to be selectively mounted on the bar 392 and comprise a horizontal wall 399 formed with openings which may be aligned with the openings 395 in the bar. Screws 400 may be used to secure the members to the bar. Said members further comprise a vertical wall 401 extending downwardly from the front edge thereof and from which extends an inwardly turned transverse lug 402.

A pivoted member 403 is mounted on a central portion

of a side edge of the change mechanism 75 by means of a pivot screw 404. Said member 403 comprises an arm 405 extending along the side of the change mechanism and terminating in an inwardly turned end portion 406. Another arm 407 of the member 403 extends to the front of the change mechanism and comprises a transverse portion 408 in which is provided a slot 409. Extending upwardly from the outer end of the portion 408 is a vertical lug 410 (Fig. 4). The pivoted member 403 is retained against pivoted movement by a screw 411 passed through the slot therein and received in a threaded opening in the front portion of the change mechanism. The lug 410 of the pivoted member 403 is adapted to engage the lug 402 on the member 398.

A coil spring 412 is secured at one of its ends to the bar 392 at a point adjacent the lug 396 and at its other end to the guide bracket 394 on the innermost of the right-hand change mechanism 75. The spring 412 tends to move the bar 392 to the right, looking at Fig. 3, in which position the arm portion 406 of the member 403 is disposed in the path of an abutment member 413 which is integral with the dispenser bar 59 and is disposed above the plate 28 (Fig. 4). The forward movement of a dispenser bar 59 will cause the abutment member 413 to engage the portion 406 of the arm 405 and rotate the member 403 in a clockwise direction, as seen in Fig. 4. This in turn will produce movement of the bar 392 to the left, looking at Fig. 4, by means of the abutting lugs 402 and 410.

The bar 392 is adapted to actuate a pivoted member 414 mounted on the release mechanism (Figs. 3, 11 and 11A). The member 414, the details of which are shown in Fig. 20, comprises a vertical lever raiser plate 415 having ears 416 extending outwardly from opposite sides thereof and provided with aligned openings 417 which receive a pivot pin 417a mounted on the pin supports 279 and 279a. The plate 415 comprises an inclined side edge 418 in which is provided a horizontal wide slot 419 and narrow slots 420, 421 and 422 (see Fig. 20).

An abutment lug 423 extends outwardly from the other side of the plate 415, said lug being disposed opposite the slot 419. The plate further comprises an upstanding wall 424 formed on the side of the plate opposite the slots 420, 421 and 422. The wide slot 419 registers with the slots 144 and 145 in the plate 95, while the slots 420, 421 and 422 register with the slots 143, 142 and 141, respectively, in the plate 95. The end portions of the nickel lever 1 and the extra lever 8 are adapted to project into the slot 419, and the end portions of the nickel levers 2, 3 and 4 are adapted to project into the slots 420, 421 and 422, respectively, as shown generally in Fig. 5. The lug 396 on the bar 392 abuts the abutment lug 423 on the plate 415 whereby slidable movement of the bar will pivot the plate 415 about the pivot pin 417a. Studs 425 (Fig. 11), received in the openings 300 of selected nickel levers or the extra lever 8, rest on the inclined edge 418 of the plate 415 adjacent the slotted portion thereof. In its normal position, as shown in Fig. 11, the plate 415 is disposed so that the inclined edge 418 thereof is in contact with the surface 95b of the plate 95. When the plate 415 is pivoted by the movement of the bar 392, the inclined edge 418 will be disposed at an angle to the surface 95b, as is best shown in Fig. 11A. The plate 415 so moved will cause those coin levers having studs 425 mounted thereon to be moved outwardly, thereby clearing the forward edge of the slide 96.

It will be apparent that securing an angle member 398 to the bar 392 in front of a selected penny coin changer mechanism 75 will permit the coin raiser plate 415 to be operated upon forward movement of the appropriate dispenser bar 59.

The operating bar 393, which is disposed over the penny change mechanisms 75 on the left-hand side of

the dispensing device, is similar to the bar 392 except that its inner end flange corresponding to the flange 393 abuts an upstanding portion 426 (Fig. 3) of one arm of a pivoted lever 427 which is horizontally mounted on a post 428 (Fig. 13) vertically positioned on the plate 28. The lever 427 is interconnected to the bar 392 by means of a link 429 which is disposed across the mid-section of the device which separates the two groups of penny change mechanisms. The link 429 comprises an offset portion 430 (Fig. 11) at one end thereof from which extends an upwardly hooked portion 431 disposed in the slot 397 of the bar 392. The link 429 also comprises a hooked portion 432 at its opposite end which engages the other arm of the lever 427 (Fig. 13).

The penny change mechanisms 75 on the left-hand side of the dispensing device are provided with pivoted members 403, and the bar 393 is provided with a detachable member 398 similar to those previously described. It will thus be apparent that forward movement of a dispenser bar 59 on the left-hand side of the dispensing device will produce slidable movement of the bar 393 to the right, looking at Fig. 3. This will cause pivoted movement of the lever 427 in a clockwise direction, thereby pulling the link 429 to the left. This in turn will cause the bar 392 to move to the left which will actuate the raiser plate 415 in the manner previously described.

It will be apparent from a consideration of Fig. 3, that all the penny change mechanisms 75 may be provided with pivoted members 403 except the mechanisms immediately adjacent the mid-section of the device. Any of the chutes 59 or 51 may thus be set to vend merchandise at five cents less than the price at which the release mechanism is adjusted with the exception of the outermost chutes adjacent the side walls of the device.

Means are provided for returning coins inserted into the dispensing device to the receptacle 17 on the front wall of the cabinet in event that a dispenser bar 59 is not operated. To this end, an elongated channel shaped bar 433 (Fig. 13) is slidably mounted in a channel shaped opening (not shown) formed in a mid-portion of the flange 30 of the assembly plate 28. The bar 433 projects through an opening (also not shown) in the front wall 12 of the casing 11 in registry with the opening in the flange 30. A handle 435 (Fig. 15) is secured to the outer end of the bar 433 and is disposed in lateral alignment with the handles 65, as best shown in Fig. 2. An extension member 436 is secured to the inner portion of the bar 433 and extends inwardly therefrom. A bracket 437 is secured to the extension member 436 being disposed transversely thereof. The bracket 437 comprises an upstanding apertured flange 438 on one end thereof and a downwardly extending apertured flange 439 on the other end thereof (Fig. 13).

The bar 433 is interconnected to the coin return bar 254. To this end, a lever 440 (Fig. 15) is pivotally mounted on the stud 252 which passes through the slot 255 in said coin return bar. One arm of the lever 440 is connected to one end of an arm 441 by a pivot screw, the other end of the arm 441 being connected to the bracket 263 on the return bar 254 by a pivot screw received in the threaded opening 264 thereof. The other arm of the lever 440 is pivotally connected to the upstanding flange 438 on the bracket 437 by means of an arm 442. It will be apparent upon consideration of Fig. 15 that, when the handle 435 is pulled outwardly, the lever 440 will be pivoted in a counterclockwise direction about the stud 252 which will move the coin return bar 254 rearwardly against the action of the spring 259 for a purpose hereinafter appearing. Upon release of the handle 435, the spring 259 will restore the coin return bar 254 to its normal position.

The flange 439 on the bracket 437 is pivotally connected to a bell crank 443 pivotally mounted on the post 286 by means of an arm 444 (a fragment of which is shown in Fig. 13) interconnecting the flange and one arm

445 (Fig. 5) of the crank. The other arm 446 of the crank is connected to a portion of the coin selector mechanism 166 (disposed on the upper portion of the plate 95) by means of a link 447 which may be utilized to operate said selector mechanism in the manner more fully described in applicant's aforesaid copending application Ser. No. 18,443 filed April 1, 1948.

Means are provided for conducting coins from the release mechanism to the receptacle 17 when it is desired that said coins be returned to a customer. To this end coin chutes 448, 449 and 450 are mounted on the central supporting wall plate 24 (Fig. 15). The coin chute 448 is designed to receive quarters which drop from the release mechanism through the slot 48 in the assembly plate 28. Said coin chute 448 comprises a vertically disposed portion which is open at its upper end and disposed in a manner to communicate with the slot 48. An inclined wall portion 452 extends from the lower end of the vertically disposed portion of the chute to the plate 24 and flanges 454 extend from the sides of the walled portions and are secured to plate 24. The front of the inclined walled portion 452 is open and communicates with an opening 455 in the plate 24. The chute 448 further comprises an auxiliary portion 456 extending laterally from a side wall of said chute and communicating therewith. The upper end of the auxiliary portion 456 is open and is disposed in a manner to communicate with the square slot 49 in the plate 28 for a purpose hereinafter appearing. Similarly, the chute 449 is designed to receive dimes which may drop through the slot 42 in the plate 28. Said chute 449 comprises walled portions which are open at the top for communication with the slot 42 in the plate 28 and also comprises a vertical front opening which registers with an opening 457 in the plate 24. The chute 450 is similarly designed to receive nickels which may drop through the slot 40 in the plate 28 and comprises walled portions which are open at the top, for communication with said slot 40, as well as a vertical front opening which registers with an appropriate opening 458 in the plate 24.

In the event that coins are inserted into the device in an amount greater than the price of an article to be vended, means are provided both for holding change and for dispensing the correct amount of change to the front of the device along with the vended article. Means are also provided for determining the lack of coins in the change holding means together with means, actuated by the determining means, for returning inserted coins to the front of the device should no change be present in the change holding means. To this end a horizontally disposed elongated rectangular plate, shown generally at 460, is mounted on the plate 24, in spaced relation thereto, by means of brackets 461 and 462 and spacing collars 462a (Figs. 13 and 15). The plate 460, the details of which are shown in Fig. 27, comprises front and rear portions 463 and 464. The rear portion 463 is provided with a longitudinally disposed rectangular shaped recess 465 on the under surface thereof and with a circular opening 466 slightly larger in diameter than a nickel. The opening 466 communicates, through the upper surface of portion 463, with the recess 465 and is spaced inwardly of the end of the plate 460. The portion 463 also has formed in its upper surface a rectangular slot 467 which communicates through the upper surface to the recess 466 and which has a width less than that of said recess 465. Similarly, the front portion 464 of the plate 460 is formed with a longitudinally disposed rectangular shaped recess 468 on the under surface thereof and is provided with a circular opening 469 slightly larger in diameter than a dime. The opening 469 communicates with the recess 468. The portion 464 also has provided in its upper surface a rectangular slot 469a communicating with the recess 468 and having a width less than that of said recess 468. Said opening 469 is disposed at the inner end of the slot 469a. The recesses

468 and 465 are longitudinally aligned with each other but their bottom surfaces are in parallel offset relation to each other.

Extending upwardly from the upper surface of the plate 460 are a pair of coin tubes 470 and 471 which communicate at their lower ends with the opening 466 and the opening 469, respectively. The upper ends of the tubes 470 and 471 are beveled toward the plate 24. Upstanding brackets 472 (only one of which is shown, Fig. 13) extending from the upper surface of the plate 460 are disposed adjacent the coin tubes 470 and 471 and the outer side of the plate.

The recess 465 in the rear portion 463 of the plate 460 is covered on its lower side by a cover plate 473 secured to the under surface of said plate 460 as by screws 474. The cover plate 473 is provided at one end with an open end slot 475 which is of such dimensions as to freely pass a nickel and is disposed in offset relation to the opening 466 in the plate 460. The other end of the cover plate 473 is provided with an open end slot 476 which is of such dimensions as to freely pass a dime. The recess 468 in the portion 464 of the plate 460 is covered by a cover plate 477 secured to the under surface of said plate 460, as by screws 474. Said cover plate 477 is provided at one end with an open end slot 478, the slotted end of the plate 477 overlapping the adjacent slotted end portion of the plate 473 to provide a through opening which is disposed in offset relation to the opening 469 in the portion 464 of the plate 460.

A rectangular shaped nickel pusher slide 479 is slidably disposed in the recess 465, said pusher being supported by the cover plate 473. Said pusher slide 479 has secured to an upper surface thereof, as by rivets, an angle member 480 upon which is a vertical lug 481 extending upwardly through the slot 467 in the plate 460. The lug 481 has a transverse opening formed therein. Similarly, a dime pusher slide 482 is slidably disposed in the recess 468, 473, said slide being supported by the cover plate 477. The pusher slide 482 has secured to an upper surface thereof an angle member 483 upon which is formed a vertical lug 484 also having therein a transverse aperture. The vertical lug 484 extends upwardly through the slot 469a in the plate 460.

The slides 479 and 482 are actuated by linkage connections to the push bars 219 and 226 (Fig. 16). To this end a horizontal post 485 is mounted on a forward portion of the vertical plate 24 (Fig. 13). A pair of vertically disposed adjacent levers 486 and 487 are mounted on the post 485, as by a pivot pin 488 passing through both levers. The lever 486 comprises a downwardly extending offset arm 487a disposed adjacent the plate 24 and pivotally connected, at its lower end, to one end of a horizontally disposed link 488a (Figs. 16 and 27). The link 488a comprises at its other end an arm 489 disposed at right angles thereto and provided with a rectangular slot 490 therein. The vertical lug 481 on the nickel pusher slide 479 is engaged in the slot 490 and is secured therein as by a cotter pin passed through the aperture in the lug. An upper arm 491 of the lever 486 extends upwardly through the slot 43 in the plate 28 and is pivotally connected to one end of a link 492 (Fig. 13). Link 492, the details of which are shown in Fig. 21, comprises a pair of parallel, offset portions 493 and 494 interconnected by a transverse portion 495. A transverse portion 496 (Fig. 13) extends downwardly from the lower edge of the portion 493 and is provided with a pair of vertically aligned openings, only one of which, 497, is shown. As shown in Fig. 13, the link 492 is connected to the arm 491 of the lever 486 by a screw passed through the lower of the two openings in the link. From the inner end of the portion 494 there extends an inwardly turned transverse flange 499 provided with an opening 500 therein. The flange 499 is disposed adjacent the flange 230 on the push bar 226. A threaded stud 501 passed through the opening 500 in the flange 499 is received in the

threaded opening 231 in the flange 230. A coil compression spring 502 is mounted on the stud 501 and is adapted to resiliently urge the link 492 toward the push bar 226.

A slotted angle bracket 503, having an outwardly extending lug 503a, is adjustably mounted on the outer face of the portion 494 of the link 492 (Fig. 21). Said lug 503a is disposed in the path of the arm 385.

The lever 487 is pivotally mounted on the pivot pin 488. An offset arm 504 extends downwardly from the pivoted portion and is disposed in spaced relation to the arm portion 487a. The arm 504 terminates short of the lower end of the arm 487a and is pivotally connected at its lower end to one end of a horizontally disposed elongated link 505 (Figs. 16 and 27). The link 505 comprises, at its other end, a curved end portion 506 extending downwardly toward the upper surface of the plate 460. From the lower end of the portion 506 there extends a horizontally disposed transverse arm 507 which has formed therein a rectangular slot 508 (Fig. 27). The vertical lug 484 on the dime pusher slide 482 extends through the slot 508 in the link 505, the latter being secured by a cotter pin passing through the apertured portion of the lug.

The lever 487 further comprises an offset arm 509 extending upwardly through the slot 43 in the plate 28, the upper end of said arm being pivotally connected to one end of a link 510. The link 510 comprises at its other end an inwardly turned transverse flange 511 formed with an opening 512 therein (Figs. 13 and 22). The flange 511 is disposed adjacent the flange 223 on the push bar 219 and is interconnected thereto, as by a threaded stud 512, with a coil spring 513 mounted thereon. The link 510 is also provided with an adjustable bracket 503 thereon having a lug 503a projecting outwardly therefrom and disposed in the path of the arm 385.

The lever 486 may be alternately connected to the push bar 219 by disconnecting the link 492 from the lever 486 and the push bar 226 shown in Fig. 13. The link 492 may then be used to replace the link 510, it being connected to the lever 486 through the upper opening 497 in the link. The flange 499 of the link 492 will then be disposed opposite the flange 223 on the push bar 219 and interconnected thereto in the manner previously described. The lever 487 may be removed to facilitate the pivotal movement of lever 486 when the variation is made. With this form of connection, slidable movement of the push bar 219 will cause slidable movement of the nickel pusher slide 479.

Means responsive to a lack of coins in the change tubes 470 and 471, for returning to a customer coins inserted into the coin release mechanism, comprises a linkage arrangement extending from the coin tubes to a deflector means mounted in the quarter and dime paths. The same comprises a bracket 514 mounted on the forward portion of the plate 460 (Figs. 13 and 27). An arm 515 is pivotally mounted, at one end thereof, to the bracket 514 and extends rearwardly toward the rear of the dispensing device and is pivotally connected at its rear end to a vertically extending link 516 (Fig. 16). The link 516 extends upwardly through the rear portion of the slot 43 in the plate 28 and has a transverse, inwardly extending lug 517 at its upper end which is disposed over the lug 240 on the pivoted lever 238, and is adapted to engage said latter lug upon downward movement of the link 516. A bracket 518 is also mounted on the rear portion of the plate 460, said bracket being offset with respect to the bracket 514. An arm 519 is pivotally mounted, at its forward end, to the bracket 518 and extends rearwardly toward the back of the device and slightly beyond the end of the arm 515. The arm 519 is pivotally connected at its rear end to a vertically disposed link 520 which also extends upwardly through the slot 43 in the plate 28 and has a transverse, outwardly extending lug 521 at its upper end which is disposed over the lug 237 on the

pivoted lever 235 and is adapted to engage the same upon downward movement of the link 520.

The arm 515 is provided with a cutout portion 522 on its bottom edge (Fig. 27) which comprises an inclined rear edge 523. The cutout portion 522 on the arm 515 is adapted to be engaged by an inclined cam edge 525 on the arm 489 of the link 488a when said link is disposed in a retracted position. This will occur when coins are present in the tube 470, the lowermost coin abutting the front edge of the bracket 480 which is connected to the link 488a. As a result there will be a slight pivoted upward movement of the arm 515. This in turn will produce upward movement of the link 516 for a purpose hereinafter appearing. Similarly, the arm 519 is provided with a cutout portion 526 on its bottom edge which comprises an inclined rear edge 527 (Fig. 27). The cutout portion 526 on the arm 519 is adapted to be engaged by an inclined cam edge 529 on the arm 507 of the link 505 upon rearward movement of said link occasioned by the presence of coins in the tube 471, the lowermost of which will abut the forward edge of the bracket 483 which is connected to the link 505. As a result, this will cause a slight pivoted, upward movement of the arm 519 which in turn will produce upward movement of the link 520 for a purpose hereinafter appearing.

Means are provided for conducting dispensed nickels and dimes from the change tubes 470 and 471 through the wall 24 to a return chute (not shown) which may be connected to the receptacle 17 on the front of the device. To this end an open end nickel chute 530 (Fig. 15) communicating at one end with the slot 475 in the cover plate 473, is mounted on the underside of the plate 460. The other end of the chute 530 communicates with an opening in the wall 24. Similarly, an open end coin chute 531 (Fig. 15), communicating at one end with the overlapping slots 476 and 478, is mounted on the underside of the plate 460. The other end of the chute 531 communicates with an opening in the wall 24.

Means are also provided for conducting nickels and dimes from the release mechanism to the change tubes 470 and 471. To this end, a pair of aligned angle brackets 532 and 533 are mounted on the underside of the plate 28 adjacent the vertical support plate 25 (Figs. 13 and 16). A rocker rod 534 is journaled in the lower ends of the brackets 532 and 533 and has mounted thereon, for pivotal movement, an open top bucket 535 (Fig. 13). The bucket 535 comprises a bottom wall 536, side walls 537 and a back wall 538. The bottom wall 536 comprises a downwardly inclined lip 539 which is disposed opposite the coin tubes 470 and 471. The interior of the bucket 535 is divided by deflectors 540 (Fig. 16) into two portions. The rear portion is disposed below the coin slot 41 in the plate 28 and is adapted to communicate, at its lower end, with the dime change tube 471. The front portion is disposed below the coin slot 39 in the plate 28 and is adapted to communicate, at its lower end, with the nickel change tube 470. Said bucket is pivoted from its normal position (shown in full lines in Fig. 13) to the position shown in dotted lines, by means of a horizontally disposed lever 504a pivotally mounted on a bracket 541 secured to a rear portion of the wall 25. The lever 504a is shown in detail in Fig. 25 and comprises one arm 543 having thereon a downwardly turned flange 544 which is adapted to engage a rear portion of the bottom wall 536 of the bucket 535. Another arm 545 of the lever 504a comprises an upstanding apertured lug 546 which is connected to a collar 547 on the operating rod 71 by a coil tension spring 548. Upon forward movement of the operating rod 71, the spring 548 will pull the arm 545 so as to rotate the same in a clockwise direction as seen in Fig. 25. This will cause the flange 544 on the lever to bear against the bottom of the pivoted bucket, moving it to the position shown by the dotted lines in Fig. 13. The nickels and dimes originally inserted into

the coin release mechanism are thus led to the change tubes for a purpose hereinafter described.

A tension spring 549 may be attached at one of its ends to the collar 547 on the operating rod 71 (Fig. 13) and at its other end to a bracket 530 disposed on a rear lower portion of the wall 25 (Fig. 12). Said spring is operative to return the operating rod 71 to its retracted position supplementing the action of the spring 73.

A guide plate 551, having inclined surface portions, is mounted on the brackets 472 on the plate 460 (Fig. 13). Said plate 551 may be fitted about the change tubes 470 and 471 and disposed with its upper end contacting the wall 24 and its lower end contacting the outer side of the plate 460. When the change tubes 470 and 471 become filled, surplus coins may roll down the guide plate 551 to a removable coin receptacle or cash box 552 (Fig. 12) which may be disposed at the bottom of the dispensing device between the walls 24 and 25. Quarters which drop from the release mechanism through the slot 47 in the plate 28 will drop directly into the coin receptacle 552.

Operation

The device embodying my invention is operated by first setting the coin levers 1, 2, 3, 4, 5, 6, 7 and 8 (Fig. 5) in a manner such that upon receipt of a predetermined number of certain coins, the release mechanism will be effective to free the operating rod 71 and thus allow a selected dispenser bar 59 to be pulled forwardly and returned to dispense an article of merchandise.

Assuming that it is desired that the vending device vend articles from the chutes 50 and 51 at a price of twenty-five cents, a single quarter may be inserted in the device or, as alternates, a combination of two dimes and one nickel or one dime and three nickels may be used. The release mechanism is adapted to operate with any one of these combinations and is accordingly adjusted in a manner which will now be described. The detachable bracket 365 is removed from the channel member 354 and the angular member 379 is removed from the channel member 370. The change dispensers are rendered inoperative by removing the links 492 and 510 connecting the push bars 226 and 219 with levers 486 and 487, respectively. Upon inserting a quarter "A" into the dispensing device, the coin will move downwardly through the plate 160 and the passageway 135 into the slot 196 of the slide 96, as shown in Figs. 9 and 14. The coin will rest on the lug 262 on the coin return bar 254 and will be disposed rearwardly of the cam edge 322 of the lever 7 which projects through the slot 153 in the plate 95 and is disposed in the slot 187 which intersects the coin slot 195 in the slide 96. Upon pulling a selected dispenser bar 59 by its handle 65, the interconnected operating rod 71 will be moved forwardly, pulling the slide 96 forwardly by means of the hooked arm 385 and its interconnected arm 387 (Fig. 6). As shown in Fig. 9A, the forward movement of the slide 96 permits the coin "A" to move the quarter lever 7 out of the slot 153. The outward movement of the quarter lever 7 pivots the member 337 resting on the edge 320 of said lever, which in turn causes pivoted movement of the coin lever raiser 342 by means of the interconnecting arm 349. The pivoted movement of the lever raiser 342 raises all of the nickel levers as well as the extra lever 8. This permits unobstructed forward movement of the coin slide 96, the operating rod 71, and thus any one of the dispenser bars 59. With the slide 96 in its forward position, the coin "A" will be moved to a position above the passageway 129 through which it will be free to fall downwardly through the slot 47 in the plate 28 into the coin receiving receptacle 552 disposed between the plates 24 and 25.

When two dimes "B" and "C" are successively inserted into the device, they will move through the path 161 and the passageway 139, into the slot 195 of the slide 96 within which the lowermost of the coins will rest on the

lug 261 on the coin return bar 254. A nickel "D" inserted into the device, moves through the path 163 and the passageway 140, into the slot 194 of the slide 96 and finally rests on the lug 260 on the coin return bar 254.

Upon pulling the selected dispenser bar 59, as previously described, the slide 96 will be moved forwardly since the lowermost dime "B," which is disposed rearwardly of cam edge 311, will cam the dime lever 5 outwardly, thereby moving the channel member 354 outwardly. This latter movement in turn will lift the extra coin lever 8 and the nickel lever 4 outwardly by the lugs on the member 354. The second dime "C" will cam the dime lever 6 outwardly, thereby moving the channel member 370 outwardly. This in turn will retract the nickel levers 2 and 3 which are engaged by the lugs 375 and 378 on the member 370. The nickel "D," which is disposed rearwardly of the cam edge 297, will cam the nickel lever 1 outwardly. In the movement of the slide 96 to its forward position the dimes "B" and "C" will be moved to a position above the passageway 127 and will thus drop downwardly through the slot 41 in the plate 28. Similarly, the nickel "D" will be moved over the passageway 125a and will drop downwardly through the slot 39 in the plate 28. The dimes dropping through the slot 41 will pass into the rear portion of the bucket 535, which is in communication with the slot 41, due to the action of the pivoted lever 540a. Said dimes will pass over the lip 539 of the bucket into the dime change tube 471. In the event the change tube 471 is filled, the excess dimes will slide down the guide plate 551 to the cash receptacle 552 which is disposed between the walls 24 and 25 at the bottom of the dispensing device. Similarly, the nickel dropping through the slot 39 will pass into the front portion of the bucket 535 and will be conducted to the nickel change tube 470. If the nickel change tube becomes filled, the excess nickels will fall into the cash receptacle by way of the guide 551.

With a one dime-three nickel combination, the dime "B" will raise the extra coin lever 8 and the nickel lever 4 as described above, while the three nickels "D," "E" and "F," will raise the nickel levers 1, 2 and 3, thus allowing the slide 96 to be pulled forwardly as described.

When the device is to vend articles at a price of twenty cents, it is apparent that two dimes may be inserted into the device or, as alternates, combinations of one dime and two nickels, or four nickels may be inserted. As still another alternate, a quarter may be inserted into the device, in which event a nickel in change will be returned. For twenty-cent setting, the extra coin lever 8 is rendered inoperative by raising it out of its normal position and using a stud disposed in the opening 334 of the lever and positioned on the lug 277 to keep said lever in its inoperative position. The detachable bracket 365 is restored to its position on the channel member 354 adjacent the side wall 357, and the angular member 379 is replaced in its position on the channel member 370. Additionally, the link 528 is disconnected from the arm 519 shown in Fig. 16 and is connected to the arm 515. Also, the push bar 219 is reconnected to the lever 486 by the link 492, the link 510 and the lever 487 being removed. Upon inserting the two dimes "B" and "C" successively in the device, they will move through the path 161 and the passageway 139 and pass into the slot 195 of the slide 96, as shown in Figs. 8 and 16. Upon forward movement of the slide 96, the lowermost dime "B" will cam the dime lever 5 outwardly, which in turn will rotate the channel member 354, as shown in Fig. 8A. The lugs 369 on the bracket 365, which is attached to the member 354, will raise the nickel levers 3 and 4. The second dime "C" will cam the dime lever 6 outwardly, which in turn will raise the channel member 370. The lugs 378 and 384 on the member 370 will raise the nickel levers 1 and 2. With all four nickel levers raised, the slide 96 is free to move forwardly in the manner previously described. The two dimes "B"

and "C" will thus be moved over the passageway 126 and will drop through the slot 41 in plate 28. When a single dime and two nickels are used, the dime will raise the nickel levers 3 and 4, in the manner previously described, while the two nickels will raise the nickel levers 1 and 2. The dimes and nickels will be moved over the dime and nickel release passageways as previously described. When four nickels, "D," "E," "F" and "G" are successively inserted into the device, the coins will come to rest vertically aligned one above the other in the slot 194 in the slide 96 as shown in Figs. 7 and 14, and upon forward movement of the slide, will cam the nickel levers 1, 2, 3 and 4 outwardly, as shown in Fig. 7A, permitting the slide 96 to move forwardly. As the slide moves forward, the pivoted lever 218 moves in a counterclockwise direction to cover the lower end of the passageway 140. This holds back all the nickels, in excess of four, which may have been inserted into the machine, and prevents the same from entering the upper end of slot 194 of the slide 96. In this manner excess coins are also prevented from falling in back of the edge 170 of the slide 96 and interfering with its retracted movement. The nickels within the slot 194 will fall through the passageway 125a and the slot 39 in the plate 28, as shown in Fig. 14A, when the slide 96 is moved to its forward position. The nickels and dimes will pass into the change tubes 470 and 471, respectively, in the manner previously described.

When a quarter "A" is inserted into the device, it will move through the path 160 and passageway 135 into the slot 196 of the slide 96, as previously described. The top of the coin will be disposed opposite the recess 176 in the slide 96. Upon forward movement of the slide, the coin will cam the quarter lever 7 outwardly which will cause the nickel levers 1, 2, 3 and 4 to be raised in the manner previously described, thereby permitting full forward movement of the slide. As the slide 96 moves forwardly, the coin "A" will abut the lug 225 on the push bar 219 which projects into the recess 176 in the slide. Continued forward movement of the slide 96 will cause the push bar 219 to move forwardly. The push bar 219 is interconnected to the nickel pusher slide 479 by the link 492, the lever 486, and the link 488a and will thus impart slide movement to the slide 479. The slide 479 normally is in a somewhat retracted position with an edge of bottom flange of angle member 480 abutting the lowermost coin in the nickel change tube 470 which coin rests on said slide. When pressure bar 219 is moved by coin "A," lever 486 will retract the slide to allow the lowermost coin in tube 470 to drop onto the plate 473, all the coins thus provide a distance equivalent to the thickness of one of said coins, and the ends of the lowermost coin will then be at the level of the bottom flange of said member 480. Upon forward movement of the pusher slide, the lowermost coin is moved to a position from which it drops through the opening 475 in the plate 473 into the coin chute 530 and is conducted to the chute (not shown) leading to the receptacle 17 on the front wall of the cabinet. It is apparent that the nickel change will accompany the vended article to the receptacle.

If no nickels are present in the change tube 470, the nickel pusher slide 479, which is normally retained in a somewhat retracted position by the abutting lowermost coin in the tube, will move forward slightly. As a consequence, the cam member 489 mounted on the link 488a, which engages the slide 479, will also be in a slightly forward position. As a result, the inclined edge 525 on the cam 489 will be disengaged from the edge 523 of the cutout portion 522 of the arm 515. This will permit the arm 515 to move downwardly about its pivot point and to also move the connected link 520 in a downward direction. As a consequence, the lug 521 on the link 520 will engage the lug 237 on the lever 235, pivoting the latter in a counterclockwise direction, which will cause

the lug 236 on said lever 235 to assume an upper position within the opening 233 in the plate 97, as shown in Fig. 16. When the quarter "A" is inserted into the mechanism, it will move through the path 160 until it strikes the lug 236 which will prevent the coin from moving into the slot 196 in slide 96 as it would normally. Instead, the coin will be deflected to the pocketed portion 165 of the plate 95, from which said coin will pass through the opening 203 in the plate 97, down the inclined chute 209, through the slot 49 in the plate 28, and, by way of the coin chute 456, will pass through the wall 24 into the chute (not shown) communicating with the receptacle 17 on the front wall of the cabinet. It follows that lack of change in the coin tube 470 will cause the inserted coin to be returned to a customer.

When it is desired that articles be dispensed at a price of fifteen cents, merchandise may be vended when the release mechanism has received one dime and one nickel or three nickels. Also, the insertion of a quarter will require a dime in change, and the use of two dimes will necessitate the return of a nickel in change. For obtaining these results, the release mechanism is adjusted with the nickel lever 4 and the extra lever 8 rendered inoperative. This is accomplished by the use of a stud inserted into the opening 301 in the nickel lever 4 to support said lever in a raised position on the adjacent guide lug 276. The extra lever 8 is raised as previously described. The detachable bracket 365 is shifted on the channel member 354 so that it is disposed inwardly of the wall 356 thereof, being secured by screws received in openings in the top wall 355 of the member. In this position, the lugs 369 on the bracket 365 will underlie the nickel levers 2 and 3. Additionally, the link 520 is reconnected to the arm 519, and the link 516 is connected to the arm 515 as shown in Fig. 16. Also, the push bar 226 is reconnected to the lever 486 by the link 492 and the push bar 219 is reconnected to the lever 487 by the link 510, as shown in Fig. 13. Upon forward movement of the slide 96 when one dime "B" and one nickel "D" has been received therein, the dime will cam the dime lever 5 outwardly which will raise the channel member 354 which in turn will raise the nickel levers 2 and 3 by the bracket 365. The nickel "D" will cam the nickel lever 1 outwardly thereby releasing the slide 96 for unobstructed forward movement.

With the three nickel combination, the inserted coins will cam the nickel levers 1, 2 and 3 outwardly to release the slide for forward movement as previously described.

When a quarter "A" is received in the slide and a dime in change is required, upon initially moving the slide forwardly the quarter lever 7 is cammed outwardly and is effective to raise the nickel levers in the manner previously described, thereby permitting full forward movement of the slide 96. The coin will also be effective in moving the push bar 219 forward, as previously described. However, the push bar 219 being connected to the dime pusher slide 482 by the link 510, the lever 487 and the link 505, the movement of said push bar 219 will impart forward movement to the dime pusher slide 482. Said dime pusher slide 482 is normally in a retracted position with its forward edge abutting the lowermost coin in the dime change tube 471. Upon forward movement of said pusher slide, the coin is moved to a position from which it drops through the opening 478, 476 in the cover plates 473 and 477 into the coin chute 531 and is thereby conducted to the return chute (not shown) leading to the receptacle 17, as previously described.

If no dimes are present in the dime change tube 471, the dime pusher slide 482 will be disposed in a slightly forward position since no coin is present to retain the same in its retracted position. Accordingly, the cam 528 mounted on the link 505 which engages the pusher slide 482 will also be in a forward position. As a result,

the cutout portion 526 on the arm 519 will not be cammed upwardly and the arm 519 will be permitted to move downwardly about its pivot point. The link 520 will also move downwardly causing the deflecting lever 235 to pivot in a counterclockwise direction and cause the lug 236 to be moved to its coin deflecting position, as previously described. The inserted quarter will thus be deflected from its normal path in the manner previously described and will be returned to the receptacle 17.

If two dimes B and C are received by the slide 96 in payment for a fifteen-cent article, a nickel in change will be returned along with the dispensed article. The two dimes successively inserted, will rest in the slot 195 in slide 96 as previously stated. Forward movement of the slide will cause the lowermost dime B to cam the dime lever 5 outwardly, thereby lifting the channel member 354 which in turn will lift the nickel levers 2 and 3 by means of the lugs on the bracket 365. The uppermost dime C will cam the dime lever 6 outwardly, which in turn will raise the channel member 370. The lug 384 on the member 379, which is secured to the channel member 370, will lift the nickel lever 1. With the nickel levers 1, 2 and 3 lifted, the slide 96 is free for full forward movement. As the slide moves forwardly, the dimes B and C are vertically separated by the member 275 which projects into the slot 152 of the slide 96. The upper portion of the dime C is disposed opposite the recess 175. As the slide continues its forward movement, the dime C will abut the lug 232 on the push bar 226 which projects into the recess 175 in the slide. The resultant movement of the push bar 226 will produce slidable movement of the nickel pusher slide 479 by means of the interconnecting link 492, the lever 486 and the link 493a. The link 492 connects the push bar 226 with the lever 486 as shown in Fig. 13. The forward movement of the nickel pusher slide 479 will dispense a coin from the nickel tube 470 in the manner previously described.

If no nickels are present in the nickel change tube 470, the nickel pusher slide 479 will be operative to cause a downward pivoted movement of the arm 515 and the interconnected link 516 as before explained. As a consequence, the deflecting lever 238 will be pivoted in a counterclockwise direction, bringing the lug 239 into a position in which it will deflect a dime into the pocketed portion 164. The deflected coin will then pass through the opening 202 in the cover plate 97, down the inclined surface 212 to the inclined chute 209 from whence it will drop through the slot 49 in the plate 28 and be returned to the receptacle 17, as previously described.

When the supply of nickels in the change tube 470 is exhausted, the nickel pusher slide 479 will be disposed in a forward position within the bottom of the tube as shown in Fig. 15. Upon subsequent insertion of nickels into the dispensing machine, said coins will be conducted to the change tube and the lowermost coin will rest on the top of the angle member 480 on the slide 479. With subsequent operation of a dispenser bar, the arm 385, during its pivoted, counterclockwise movement, will engage the lug 503a on the bracket 503 on the link 492, thereby imparting a slight forward movement to the link. This in turn will cause the lever 486 to pivot sufficiently to retract the slide 479, thereby permitting the lowermost coin to lie flat on the upper surface of the slide 479. When a dispenser bar 59 is again pulled forward, the slide 479 will be moved to its fully retracted position, thus causing the coin to drop to the cover plate 473 with the forward edge of the slide 479 abutting the edge of the coin. Similarly, the coin slide 482 may be restored to its operative position after the supply of dimes in the dime change tube 471 have been exhausted and subsequently inserted dimes have been passed through the release mechanism into the change tube 471. In this circumstance, the bracket 503 on the link 510 is engaged by the arm 385 to effect retraction of the slide 75

482 in a manner similar to that by which the coin slide 492 is retracted.

It will be understood that articles may be dispensed from the above described mechanism at prices between fifteen and twenty cents or between twenty and twenty-five cents. For example, an article may be vended at a price of fourteen cents. In this case, the coin release mechanism is set for fifteen cents as described above, and in addition, the penny changer mechanism 75 is set to dispense a penny in change. The penny change mechanism 75 is pre-set to return a single penny by use of the proper slide 78 which operates in the manner more fully described in my application Ser. No. 670,135. The penny in change drops through the slot 38a in the plate 28 and is returned with the vended goods to either the receptacle 17 or 18 on the front of the cabinet by means of chutes (not shown). Similarly, the penny changer 75 may be set to return two, three or four pennies, depending upon the price of the vended merchandise. It will also be understood that pennies may be returned as change, together with change from the change tubes 470 and 471. For example, with the device adjusted for twenty cents, and with an article to be vended at a price of eighteen cents, the insertion of a quarter into the machine will return a nickel in change from change tube 470, as above described, and two pennies will be discharged from the penny change mechanism 75. With the device set at fifteen cents and an article to be vended at a price of twelve cents, the insertion of a quarter will result in the return of a dime from the change tube 471 and three pennies from the penny change mechanism.

If it is desired that selected chutes vend articles at five cents less than the price at which articles are to be vended from the remaining chutes, an angle member 398 is attached to the bar 392 or the bar 393 opposite the selected chute. The angle member 398 actuates the bar 392 or the bar 393, which in turn imparts pivoted movement to the lever raiser plate 415 in the manner previously described. If the release mechanism is set for fifteen cents, for example, the insertion of ten cents either as a dime or two nickels will allow articles to be vended from the selected chute. In addition to setting the coin release mechanism for a fifteen-cent operation wherein the extra lever 8 and the nickel lever 4 are permanently raised, as previously described, studs are inserted in the opening 309 on the nickel levers 1 and 3. Said studs will rest on the inclined side edge 418 of the pivoted plate 415. With the insertion of a dime, the nickel levers 2 and 3 will be raised by the bracket 365, as previously described, and the pivoted clockwise movement of the plate 415 will raise the nickel lever 1. With the insertion of two nickels, the pivoted plate 415 will raise the nickel levers 1 and 3 by means of the studs resting on the inclined edge of the plate 415. The second, or uppermost, nickel in the coin slide will raise the nickel lever 2.

With the release mechanism set for a twenty-cent operation, wherein the extra lever 8 only is permanently raised, the insertion of fifteen cents as a dime and a nickel, or three nickels, will likewise allow the vending of articles from the selected chute. In this case, the studs are shifted from the nickel levers 1 and 3 to the nickel levers 2 and 4. The dime in the slide 96 will then raise the nickel levers 3 and 4 in the manner previously described, the nickel will raise the nickel lever 1, and the pivoted plate 415 will raise the nickel lever 2. With the insertion of three nickels, on the other hand, the pivoted plate 415 will raise the nickel lever 4 while the nickels will raise the nickel levers 1, 2 and 3.

With the coin release mechanism set for a twenty-five cent operation, wherein the detachable bracket 365 is removed from the channel member 354 and the angular member 379 is removed from the channel member 370, the studs are shifted to the nickel levers 1 and 3 and a stud is also inserted in the opening 333 in the extra lever

8. The insertion of twenty cents as two dimes, a dime and two nickels or four nickels, will then allow articles to be vended from the selected chute. With the insertion of two dimes, the first, or lowermost, dime in the slot 195 of the slide 96 will raise the extra coin lever 8 and the nickel lever 4, while the second, or uppermost, dime will lift the nickel levers 2 and 3. The pivoted plate 415 will raise the nickel lever 1. With the combination of a dime and two nickels, the dime will raise the extra coin lever 8 and the nickel lever 4, as before, and the two nickels will raise the nickel levers 1 and 2 while the pivoted plate will raise the nickel lever 3. With the combination of four nickels, the nickel levers 1, 2, 3 and 4 will be lifted by the coins while the pivoted plate 415 will lift the extra lever 8, thus allowing full forward movement of the slide 96.

In the event that coins have been received by the release mechanism and, previous to pulling a dispenser bar 59, a customer desires for any reason that the coins be returned to him, such return is effected by pulling the handle 435 on the mid-section of the front wall of the cabinet. It will be understood that coins inserted into the dispensing machine move through the coin paths and are directed into the appropriate vertical slots 194, 195 and 196 in the coin slide 96. The lowermost of the coins in the slots rest on the coin return bar 254, with the quarter positioned on the lug 262, the lowermost dime positioned on the lug 261 and the lowermost nickel positioned on the lug 260. When the handle 435 is pulled forward, the attached channel member 433 will cause forward movement of the coin return bar 254 by means of the interconnected arm 441, the lever 440 and the arm 442. With the coin return bar in its forward position, the lugs 260, 261 and 262 will no longer support the coins previously positioned thereon, and said coins will be free to fall through the passageways 130, 128 or 126 which communicate with the slots 48, 42 and 40 in the plate 28, respectively. The slots 48, 42 and 40 communicate with the return chute (not shown) which leads to the receptacle 17 by way of the chutes 448, 449 and 450, respectively. Upon releasing the handle 435, the coin return bar 254 is returned to its retracted position by the spring 259.

If, for any reason, coins are retained in the slide 96 while it is in its forward position, it will readily be understood that said slide cannot be returned to its retracted and normal position so long as the coins remain in the slide. This is due to the construction of the coin levers. The straight edge 298 on the projection 294 of the nickel levers will be abutted by nickels in the slot 194 of the slide when said slide is in the forward position, thus preventing retracted movement of the slide. Similarly, the straight edge 312 of the projection 310 on the dime levers 5 and 6 will abut dimes contained in the slot 195 of the slide, and the transverse edge 321 of the projection 319 on the quarter lever 7 will abut a quarter contained in the slot 196 of the slide, thus preventing retracted movement of said slide after the latter has assumed its forward position and still retains coins therein. The nickel coin levers 1, 2, 3 and 4, and the extra lever 8, may be cleared, if necessary, by manual operation of the arm 349. Upon pulling the arm 349 forward by grasping the lug 351, the interconnected lever raiser 342 will raise the nickel levers and the extra lever, thus releasing coins which may have been held in the slide 96 thereby.

The above described embodiment of my invention may be also adapted for dispensing change in the form of nickels, or nickels and a dime, in exchange for a quarter, or nickels in return for dimes inserted therein. In this arrangement, no merchandise is vended from the chutes 50 and 51 immediately adjacent the mid-section of the machine. The coin tubes 72 on the penny change mechanisms 75 in front of the selected chutes, may be of a size sufficient to accommodate nickels instead of pennies. With the release mechanism set for fifteen-cent sales, as above described, the coin tube 76 on the selected chute 50 on

the left-hand side of the machine is set by means of the proper slide 78 to return three nickels. Upon receipt of a quarter in the release mechanism, the three nickels from the tube 77 will pass through the slot 38a in the plate 28 and will be returned together with a dime from the change tube 471. With the release mechanism set for twenty-cent sales, the coin tube 76 is arranged to return four nickels. In this case, the four nickels from the tube 76 will be accompanied by a nickel from the change tube 470. The change in nickels and dimes will be received in the receptacle 17. As a further alternative, the coin tube 77 may be altered to hold dimes and is then adapted to return two dimes in change together with a nickel from the change tube 470 upon the insertion of a quarter when the device is set for twenty-cent sales.

The change tube 77 on the right-hand side of the machine in front of the selected chute 51, may be adapted to return two nickels in exchange for a dime inserted into the release mechanism. In this case, with the release mechanism set for fifteen-cent sales, the coin tube 77 is adjusted to dispense two nickels using the five-cents-less attachment on the bar 392 in front of the selected chute. The nickels as change will pass through the slot 38a in the plate 28 and may be returned to the receptacle 18.

The foregoing detailed description has been given for clearness of understanding only, and no unnecessary limitations should be understood therefrom, but the appending claims should be construed as broadly as permissible in view of the prior art.

I claim:

1. In combination, a support, a control member movably mounted thereon, means for moving said control member, coin operated means to releasably lock said control member against movement, said last means comprising first, second, third and fourth nickel latches having means to block movement of said control member, said control member having means to receive first, second, third and fourth nickels, said latches having means adapted to be engaged by said four nickels, respectively, to move said latches out of blocking position upon initial movement of said control member, an extra latch having means to block movement of said control member, first and second dime operated members, said control member having means to receive first and second dimes, said dime operated members having means engageable by said dimes, respectively, to move said dime operated members upon initial movement of said control member, a quarter operated member, means on said control member to receive a quarter, said quarter operated member having means adapted to be engaged by said quarter for moving said quarter operated member upon initial movement of said control member, means controlled by said quarter operated member to move said nickel latches and said extra latch out of blocking position upon moving said quarter operated member, whereby to permit movement of said control member upon receipt of a quarter, only, in said control member, means controlled by movement of said first dime operated member to move the extra latch and the fourth nickel latch out of blocking position, 50 means controlled by movement of the second dime operated member to move said second and third nickel latches out of blocking position, whereby the control member may also be moved by receipt therein of either two dimes and one nickel or one dime and three nickels, a plurality of penny storing means, a merchandise ejecting means associated with each penny storing means, means controlled by each of said ejecting means for actuating the means for moving the control member, and means controlled by each ejecting means for dispensing a predetermined number of pennies stored in the penny storing means associated therewith.

2. In combination, a movable control member, means to lock said member against movement, coin receiving means, means controlled by either a coin of first denomination, or two coins of second denomination, or a coin

of second denomination and three coins of third denomination, received in said coin receiving means, to release said locking means, a plurality of operating members, means to connect each operating member to said control member for moving the control member upon operating any one of said operating members, means for storing coins associated with each operating member, and means controlled by each operating member for dispensing a predetermined number of coins from the coin storing means associated therewith.

3. In combination, a movable control member, means to lock said member against movement, coin receiving means, means controlled by insertion in the coin receiving means of either a quarter, two dimes and a nickel, or a dime and three nickels, to release said locking means, a plurality of operating members, means to connect each operating member with said control member for moving the latter upon operation of each operating member, a coin storing member associated with each operating member, and means controlled by the operation of each oper-
